MEANS FOR POSITIONING AND HOLDING
FASTENERS IN EXPLOSIVELY ACTUATED
FASTENER DRIVING TOOLS

Ben Weingart, Los Angeles, Calif.

Application June 7, 1951, Serial No. 230,386

7 Claims. (Cl. 1—44.5)

1

This invention is concerned with a fastener applicator, that is, with a device for applying fasteners, or the like, and it is more specifically concerned with that type of device wherein an explosive charge is employed to drive or propel the fastener or element which is to be applied. It is a general object of the invention to provide a simple, practical, improved applicator or fastener handling device of the general character referred to which device serves to effectively and dependably handle fasteners that are free of retainers or special structural features serving to retain them prior to application.

Mechanisms or devices of the general character to which this invention relates can, in practice, be employed to handle elements of various kinds, and since it is common for such devices to be employed for the handling of fasteners, I will refer to the invention as being concerned with a fastener handling device. However, I wish it understood that the invention is in no way limited or restricted to the use to which the elements handled by the device are put or the purpose that they ultimately serve, and it is for this reason that I employ the term "fastener" to mean any element subject to being handled by mechanisms of the general class or character that I refer to.

Devices are in common use handling fasteners or like or comparable elements and serving to apply such fasteners to objects such as concrete bodies, and the like, by means of force developed by explosive charges. It is common in this type of device to provide the fasteners with flexible or deformable retainers serving to, in effect, releasably retain the fasteners in position to be actuated preliminary to their being driven. Retainers such as I refer to are, in effect, washer-like elements generally not desirable in the finished structure or installation and requiring manufacture and application to the fasteners. Further, such retainers commonly leave fragments in the applicators making it necessary to clean out such applicators after each operation.

It is a general object of this invention to provide a fastener applicator of the general character referred to characterized by a fastener retaining means that serves to effectively and dependably retain an ordinary or simple fastener free of any special devices or mechanical features serving as retaining means.

Another object of this invention is to provide a fastener retaining means in a structure of the general character referred to serving to hold

2

fasteners by magnetic action, all of which in no way impairs, complicates or interferes with the handling of the fasteners or with their being driven as may be the case when the fasteners are complicated by special retaining devices such as I have mentioned above.

Another object of this invention is to provide a fastener handling device of the general character referred to employing a magnetic fastener retaining means which is of simple, inexpensive construction and which in no way complicates or impairs the general construction of the device.

It is another object of this invention to provide a fastener handling device of the general character referred to provided with a magnetic fastener retaining means in which the magnetic action is gained by means of a simple, inexpensive, elongate bar magnet disposed relative to the barrel of the device so that an end of the magnet is in position to effectively hold a fastener ready for operation.

It is another object of this invention to provide a fastener handling device of the general character referred to in which a magnetic fastener retaining means is provided characterized by an annular or tubular magnet concentric with the barrel of the device and polarized so that it has ends either or both of which may serve to retain a fastener ready for operation.

It is another object of this invention to provide a fastener handling or holding device of the general character referred to in which a magnetic fastener retaining means is provided, which means is characterized by an annular sectional magnet concentric with the barrel of the device and polarized so that each section is, in effect, a U-type or U-shaped magnet, with the result that the holding action is, in effect, that of a multiplicity of magnets rather than one only.

It is another object of this invention to provide a structure of the general character referred to in which the barrel of the applicator is provided at its breech end with an enlargement or bore accommodating an insert, which insert may constitute or form a carrier for the magnet provided by the present invention serving to hold the fastener in position to be operated by a charge engaged or inserted in the insert.

The present invention is applicable to fastener applicators, generally, and it can be advantageously applied to applicators wherein the barrel through which the fastener is driven by the explosive charge is related to the other parts in various ways, and it can be applied to appli-

cators characterized by various firing mechanisms, features of control, and other like characteristics.

The fastener retaining means of the present invention involves a magnet, preferably a permanent magnet. The barrel of the structure is provided with an opening to accommodate the magnet and a suitable mounting means mounts the magnet in a suitable operating position or in the opening of the barrel. It is preferred that the mounting means be formed of material that is non-magnetic.

In the case of a typical fastener having an elongate shank and an enlargement or head on one end, the fastener is applied to the barrel or to the bore of the barrel and a part of the fastener such as the head, when adjacent the polarized end of the magnet, is held against movement in the barrel unless it is deliberately forced therefrom. The parts are arranged and related so that when the fastener is thus held in the barrel, the explosive charge is accommodated in the barrel above the fastener and a suitable closure or breech block, and other features, may be incorporated to the end that when the charge is ignited, the fastener is driven down through the barrel and into the work.

In the case of a fastener holding means wherein the magnet is annular or tubular in form, either a continuous annular member or a sectional annular member, the magnet is preferably located at the breech end of the barrel and is there accommodated by an opening in the barrel and a suitable mounting means is provided supporting the magnet in the desired position relative to the bore of the barrel.

In the case of a construction wherein the barrel is characteristically separable from the other parts to facilitate loading or charging of the structure, it is common to provide a removable insert in the barrel at the breech end, which insert is accommodated in an enlargement of the barrel opening or bore in the form of a counterbore. The annular magnet of the present invention can be carried by the insert or it can be accommodated in an extension of the counterbore that carries the insert so that the magnet is concentric with the fastener handling bore of the barrel and its central opening may be of the same size as the bore of the barrel. The mounting means holding the annular magnet may involve a sleeve around the magnet and flanges at the ends of the magnet. The insert provided at the breech end of the barrel and serving as a mounting or holder for the explosive charge may be employed or utilized as the means for retaining the fastener holding magnet in the extension of the counterbore.

The various objects and features of my invention will be fully understood from the following detailed description of typical preferred forms and applications of the invention, throughout which description reference is made to the accompanying drawings:

On sheet 1 of the drawings, and in Figs. 1 to 5, inclusive, I illustrate the invention applied to or accommodated in a gun type applicator in which the structure is such that the barrel is demountable to facilitate loading. Fig. 1 is a view illustrating the applicator and showing it from one side, certain parts being broken away to show in section. Fig. 2 is an enlarged detailed sectional view of a portion of the structure shown in Fig. 1 this view showing a fastener positioned in the barrel immediately below the propelling charge 75

and adjacent the fastener retaining or holding means. Fig. 3 is a sectional view of the upper end portion of the barrel showing the barrel detached from the other parts and showing the fastener holding means of the present invention in position in the barrel. Fig. 4 is a detailed transverse sectional view taken as indicated by line 4-4 on Fig. 3 and showing the magnet and its surrounding holder in section, and Fig. 5 is an enlarged vertical sectional view of the fastener retaining means of the present invention, showing it separate from the other parts of the structure.

On sheet 2 of the drawings Fig. 6 is a view similar to Fig. 2, illustrating a construction wherein the barrel insert is combined with the magnet holder so that these parts act as a unit. Fig. 7 is a transverse sectional view taken as indicated by line 7-7 on Fig. 6, showing the magnet as an annular or tubular sectional construction. Fig. 8 is a perspective view of the magnet illustrated in Figs. 6 and 7, showing it separate from the other parts. Fig. 9 is a view similar to Fig. 6, illustrating a construction wherein the magnet, which is tubular in form, is employed in the barrel as an insert and serves as the carrier for the charge by which the fastener is driven. Fig. 10 is a view of the magnet shown in Fig. 9 and illustrating it separate from the other parts and combined with a fastener, and Fig. 11 is a view similar to Fig. 9 showing a somewhat different adaptation.

In the form of the invention illustrated on Sheet 1 and in Figs. 1 to 5 of the drawings, the principal or main elements of the applicator 35 constitute a mechanism of a type wherein the barrel is detachable from the other parts to facilitate loading, this being the general form or type of mechanism that is the subject of Patent No. 2,479,431 to R. Temple, issued August 16, 1949.

In this form of the invention, there is a barrel B' elongate and tubular in form, and at the lower end of the barrel there is a shoe 10'. A collar portion 13' is provided around the upper or breech end of the barrel B' and has a block portion G' that closes the upper end of the said barrel. An element or body 11' is carried on the collar portion 13' and a portion thereof depends from said collar portion and carries a spring 19 that carries the shoe 10'. A spring 16' within the body 11' normally yieldingly holds the collar portion 13' in a down position relative to said body until such time as the body 11' is depressed to fire the applicator. A firing pin 55 H' is provided to be operated by a spring 22', and a control mechanism J controls the action of the mechanism and particularly the firing pin H' so that the applicator is fired when the body 11' is depressed.

The barrel is detachable from the collar 13' since it is joined thereto by a coarse threaded connection 30. A handle 30' is provided at the upper end of the body 11', and the various parts are arranged and related so that through suitable manipulation or operation of the handle 30' the control means J operates, releasing the firing pin H' so that it operates into the block portion G' and fires the charge C in the upper end of the main portion 12' of barrel B'. In the particular case illustrated, the charge C is carried in a removable insert 31 engaged in an opening or bore 32 that extends into the main portion 12' of the barrel from its upper end in alignment with the bore 31' thereof.

The fastener retaining or holding means K'

provided by the present invention is characteristically such as to make wholly unnecessary any additions or accessories to the fastener F', and it is essentially a magnetic means.

The fastener F' shown in the drawings has an elongate shank 40' and an enlargement or head 41' at the upper end of the shank, the head being engaged on the shank through a threaded connection 93.

The means K' provided to hold the fastener in the desired position in the barrel and relative to the charge C involves a magnet M', and the main portion 12' of the barrel has an opening 50' therein accommodating the magnet M', and there is a magnet mounting means 51'.

In this form of the invention, the magnet M' is of continuous annular or tubular form. In the particular case illustrated, the bore or opening 95 through the magnet M' is enlarged or relieved at 96 or between the ends of the magnet, as shown in the drawings.

The opening 50' in the main portion 12' of the barrel is provided to accommodate the magnet and its mounting and is preferably a continuation of the counterbore 92 terminating at a shoulder 96 that faces upwardly.

The mounting means 51' for the magnet M' is shown as a structure formed of non-magnetic material such as non-magnetic stainless steel, or the like, and it involves a sleeve 52' surrounding the magnet and end flanges 97 at each end of the sleeve and overlying the ends of the magnet all as best shown in Fig. 5 of the accompanying drawings.

The assembly formed by the magnet M' and the magnet mounting means 51' is inserted into the opening 50' through the counterbore 92 until the assembly rests upon the shoulder 96. The parts are related and formed so that when the magnet M' in its mounting means 51' is thus engaged in the opening 50' the bore 95 of the magnet M' is concentric with the bore 31' of the barrel B'. It is preferred that the bores 31' and 95 be formed so that they are of the same diameter. When the assembled magnet and its mounting means are in place, the liner or insert 91 can be inserted and serves as a retainer for the assembly.

In the particular case illustrated, the bore or opening 99 in the liner or insert 91 may be somewhat smaller in diameter than the bore 31' so that the lower end thereof forms a stop against which the head 41' of the fastener F' can be engaged. When a fastener F' having a head 41' of magnetic material is inserted in the structure as shown in Fig. 2 either end or both ends of the magnetic sleeve M' serves to hold the fastener F' in the desired position in the barrel. The holding of the fastener F' is such that when the charge C is ignited, as by means of the firing pin H', the fastener F' is released and driven downwardly in the barrel in the desired manner.

With the form of construction illustrated in the drawings, the cartridge C is assembled into the upper end of the main portion 12' of the barrel when that portion is detached from the collar 13', and the fastener F' can be inserted into said barrel portion 12' from its upper end ahead of the cartridge to a position where it is held by the magnet M'.

So far as the present invention is concerned, the insert employed in the barrel and the fastener holding means can be combined to, in effect, form a unit subject to being handled as

such, and in the form of the invention illustrated in Figs. 6 and 7 of the drawings such a construction is disclosed. In this case, the insert 91b has the sleeve portion 52b of the magnet mounting means 51b integrally joined thereto and projecting therefrom to enter the extension 50b of the bore 92b that accommodates the insert 91b. The mounting means for the magnet is thus combined with the insert as an integral part thereof so that these elements of the structure are subject to being handled as a unit. In carrying out this construction, it will be obvious that the magnet employed in the mounting means 51b may be the same as the magnet M' hereinabove described, and shown in Figs. 2 to 5, inclusive.

In carrying out the invention, the magnet employed, when tubular in form, can be of sectional construction, that is, it may be other than a continuous annular element, for instance, it may be formed of a plurality of sections which make up an annular structure or assembly. Such a magnet is illustrated in Figs. 6, 7 and 8, in which case the magnet M^b, instead of being a continuous annular element or sleeve-like part, is formed of sections X and Y which assemble or combine to form an annular magnet unit. In the particular case illustrated, the magnet unit is split or divided diametrically and longitudinally, so that the sections X and Y are semi-circular in cross section, and are of equal extent circumferentially of the magnet and combine to form a complete annular assembly. In practice, the abutting edges 110 of the magnet sections X and Y may be made to come together, or they can be insulated from one another, as circumstances may require. In this form of magnet construction, the magnet sections X and Y are of different polarity at the portions adjacent the edges 110, and as a result of this, the polarized parts extend longitudinally of the magnet sections or from one end of the magnet assembly to the other. The magnet sections are arranged or related relative to each other in the most advantageous manner, and the assembly of sections is inserted in the magnet mounting means so that the sections are held in the assembled relation. In the case illustrated, the two magnet sections X and Y held in the magnet mounting means 51 serve to effectively hold a fastener throughout the portion thereof that is within the magnet. In the case illustrated, a fastener F' is shown having an elongate threaded head 41b and when the head is in the structure as shown in Fig. 6 it will be held throughout its length.

So far as the broader principles of the invention are concerned, the magnet provided for holding the fastener and the insert for carrying the charge may be combined or consolidated as a single part. To illustrate such a modified construction I have, in Figs. 9 and 10, illustrated a construction wherein the magnet M^c is provided as an insert that carries the charge. I have shown this element or combined magnet and charge holding insert mounted in the barrel by a non-magnetic member 59c. In Fig. 11 I have shown a combined charge holder and magnet part mounted directly in the barrel of the gun.

Referring specifically to Figs. 9 and 10 of the drawings, the element M^c is an elongate tubular element carried in the bore 92c provided in the main portion 12' of barrel B'. The element M^c is a magnet having a bore or longitudinal open-

ing 99^c such as to receive the charge C. In this case, the element M^c is detachably mounted in the bore 92^c through a holder 59^c of non-magnetic material fixed in the bore 92^c, and the arrangement of parts is such that the innermost end of the combined insert and magnet M^c is exposed or in position to effectively hold the head 41 of a fastener inserted in the construction immediately ahead of the charge C. In the particular case illustrated, the element M^c, which is a combined insert and magnet, can be arranged in the structure with either end innermost to hold the fastener, and in the case illustrated, each end of the element M^c is recessed at 115 to effectively receive and guide the head 41 of the fastener in the manner clearly illustrated in Fig. 10 of the accompanying drawings.

In the case illustrated in Fig. 11 the member M^d is of the same type as that just described, that is, the same as that shown in Figs. 14 and 15, except that instead of being mounted in the bore of the barrel through a holder, it is mounted directly in the bore of the barrel, there being no insulating sleeve between the member M^d and the barrel. In other respects the member M^d may be the same as the member M^c shown in Figs. 9 and 10.

Having described only typical preferred forms and applications of my invention, I do not wish to be limited or restricted to the specific details herein set forth, but wish to reserve to myself any variations or modifications that may appear to those skilled in the art and fall within the scope of the following claims.

Having described my invention, I claim:

1. A gun type fastener applicator including, a barrel adapted to receive the fastener and having an enlarged opening therein concentric with the bore of said barrel, a firing means adapted to ignite a fastener driving charge, and a fastener holding means including, a magnet substantially filling said opening in the barrel with a pole of said magnet holding the fastener in an unactuated position in the barrel; and a mounting of non-magnetic material surrounding and supporting the magnet in said opening.

2. A gun type fastener applicator including, a barrel having a bore adapted to receive the fastener and having an enlarged opening therein concentric with the bore of said barrel, a firing means adapted to ignite a fastener driving charge, and a fastener holding means including, a magnet substantially filling said opening in the barrel with a pole of the magnet holding the fastener in position in the barrel preparatory to firing the charge.

3. A gun type fastener applicator including, a barrel having a fastener receiving bore, and an enlarged, annular opening in the bore of said barrel and concentric therewith, a firing means adapted to ignite a fastener driving charge, and a fastener holding means including an annular magnet in the opening in said barrel and sub-

stantially filling the same with a pole of said magnet effective to hold a fastener in the bore of said barrel.

4. A gun type fastener applicator including, a barrel adapted to receive the fastener and having an enlarged annular opening in the bore of said barrel and concentric therewith, a firing means adapted to ignite a fastener driving charge, and a fastener holding means including, an annular magnet composed of a plurality of arcuate sections mounted in said opening and substantially filling the same, said sectional magnet holding the fastener in position in the barrel preparatory to igniting the fastener driving charge.

5. A gun type fastener applicator including, a barrel adapted to receive the fastener and having an opening therein, a firing means adapted to ignite a fastener driving charge, and a fastener holding means including an insert engaged within the opening in the barrel and including a charge carrying portion and a continuous tubular magnet portion projecting longitudinally of the barrel from the charge carrying portion, said magnet serving to hold a fastener in position in the barrel preparatory to firing the charge in an unactuated position in the barrel.

6. A gun type fastener applicator including, a barrel adapted to receive the fastener and having an opening therein, a firing means adapted to ignite a fastener driving charge, a fastener holding means including an insert within said opening in the barrel and including a charge carrying portion and a tubular magnet composed of a plurality of arcuate sections projecting longitudinally of the barrel from the charge carrying portion of said insert to hold a fastener in a position on the barrel preparatory to firing the charge.

7. A gun type fastener applicator including, a barrel adapted to receive the fastener and having an enlarged opening therein concentric with the bore of the barrel and at the breech end thereof, a firing means adapted to ignite a fastener driving charge, and a fastener holding means including a tubular insert engaged in and substantially filling the opening in the barrel and adapted to accommodate and carry a fastener driving charge and including a magnet extending longitudinally of the barrel and adapted to hold a fastener in the barrel forward of the charge.

BEN WEINGART.
